UNITED STATES PATENT OFFICE

RALPH O. CLARK, OF MEMPHIS, TENNESSEE

DESIGN FOR A SERVING TRAY

Application filed February 9, 1931. Serial No. 38,599. Term of patent 3½ years.

To all whom it may concern:

Be it known that I, RALPH O. CLARK, a citizen of the United States, residing at Memphis, in the county of Shelby and State of Tennessee, have invented a new, original, and ornamental Design for Serving Trays, of which the following is a specification, reference being had to the accompanying drawing, forming a part thereof.

Fig. 1 is a perspective view of a serving

tray viewed from the lower left-hand corner; and

Fig. 2 is a diagrammatic cross section taken transversely through the tray to show the flat bottom and contour of the side edges.

I claim:

The ornamental design for a serving tray as shown.

RALPH O. CLARK.
